UNITED STATES PATENT OFFICE.

GEORGE E. CAMPBELL, OF PITTSBURG, PENNSYLVANIA.

VOTOMETER.

No. 830,879.

Specification of Letters Patent.

Patented Sept. 11, 1906.

Application filed July 19, 1905. Serial No. 270,414.

To all whom it may concern:

Be it known that I, GEORGE E. CAMPBELL, a citizen of the United States, residing at Pittsburg, in the county of Allegheny and State of Pennsylvania, have invented new and useful Improvements in Votometers, of which the following is a specification.

The invention relates to an indicator-votometer designed for use to indicate the individual vote of the members of a legislative or other body.

The main object of the present invention is to provide electrical means whereby the votometer may be suitably and accurately actuated from the desk of the individual.

Another object of the invention is to provide the structure with distinguishing characteristics whereby the voter may be informed by inspection as to the character of his vote, whereby to guard against inaccuracies possibly incident to a shunting or diverting of the energizing-current.

The invention in its preferred details of structure will first be described in the following specification, reference being had particularly to the accompanying drawings, where-

in—
Figure 1 is a plan illustrating the relative situation of the individual desks and the votometer. Fig. 2 is an enlarged plan of the push-button holder. Fig. 3 is an enlarged front elevation of the votometer proper. Fig. 4 is a broken transverse section of the same. Fig. 5 is a detail perspective illustrating the arrangement of the drop-shutters and the means for mechanically restoring them to normal or inoperative position. Fig. 6 is a diagrammatic view illustrating the preferred form of electric circuit for operating the votometer. Fig. 7 is a similar view showing a modified form of circuit.

Referring to the drawings, and particularly Figs. 3, 4, and 5, the votometer proper of my invention comprises a casing 1 of suitable size and preferably rectangular in section. The face 2 of the casing, which may be of any material desired, is provided with a plurality of rectangularly-arranged openings 3. The face-plate is divided into vertical columns 4, each column including two vertical columns of openings, and by preference these columns are suitably identified, as A, B, and C in the instance shown, it being understood that as many columns as may be desired are contemplated. The face-plate is also divided into

transverse horizontal divisions 5, preferably numbered in consecutive order and including but a single transverse row of openings 3. The individuals for whose use the votometer is designed are each assigned in regular order, 60 the openings 3 included within one vertical column—that is, each member has two horizontally-alined openings, one of which is devoted to displaying an affirmative vote and the other to displaying a negative vote. 65

Resetting-shafts 6 are mounted for pivotal movement in the side walls of the casing 1, extending transversely of the casing and slightly in rear of the openings 3 therein, being equal in number to the number of horizontal 70 divisions of the face-plate and supported in a plane slightly above the upper edge of the respective openings with which the particular shaft cooperates. Shutters 7 are loosely mounted on the respective rods 6, each of said shutters preferably including a metallic plate suitably inscribed to indicate a vote. A shutter is provided for each of the openings 3 and are arranged in pairs, one indicating an affirmative vote and the other a negative 75 vote. Each member of the voting-body will thereby control a pair of shutters arranged on one of the shafts 6 and so positioned that when lowered to operative position the face of said shutter will be exposed through the 80 particular opening 3 of that set of openings provided for the particular member. By preference one of the shutters, or both, as may be desired, are distinctively colored, so that a voter may know from the inspection 85 of the votometer which vote has been registered by observing the color of the shutter without necessity of approaching sufficiently close to the casing to read the inscription on the shutter. 90

The shafts 6 are provided with resetting-levers 8, which depend from said shaft intermediate each respective pair of shutters, and is provided at its lower or free end with a transverse bar 9, designed to project beyond 100 the contiguous edges of and bear against the faces of the neighboring shutters, as clearly indicated in Fig. 5.

The affirmative and negative shutters of the particular member are controlled through 105 push-buttons 10 and 11, respectively, suitably mounted in a holder 12, seated in the desk 13 of the particular member. Intermediate the push-buttons 10 and 11 is arranged a lamp or other visual signal 14, de- 110

signed to be energized upon the operation of either of the push-buttons to indicate to the member that his vote has been registered. By preference the visual signal is designed to remain in signaling condition until the votometer has been reset to return all shutters to normal or inoperative position, thus insuring the member that his vote remains as originally indicated until the counting of the 10 votes and the resetting of the apparatus.

In Fig. 6 I have indicated the preferred circuit for the operation of the shutters, wherein 15 represents an electromagnet connected by a wire 16 through a battery 17 to the movable point 18 of the push-button 10, the fixed point of this button being connected by a wire 19 with the fixed point 20 of the button 11. The movable point 21 of the button 11 is connected by a wire 22 through a battery 23 to a coil 24, similar in all respects to the coil 15. The coils 15 and 24 are arranged immediately in rear of shaft 6 within the casing and are each designed to actuate a pivot-latch 25, supported within the casing 25 and so arranged that when the latch is in normal position shoulder or offset 26 thereon near the upper end will support the respective shutter and hold the same elevated or in normal position. The upper end of the latch 25 adjacent the coil 15 is provided with an armature 27, connected directly through a wire 28 with the lamp 14, the remaining lamp-terminal 29 terminating in a contact-point 30 in a position to be engaged by the metallic shutter 7 when the same has been dropped to lowered or voting position, as indicated in dotted lines in Fig. 6. The negative shutter 7 is also arranged to close the lamp-circuit when in operative position through contact 40 with a fixed point 31, over which a wire 32 leads to and is electrically connected with the wire 28. The affirmative shutter is connected by a wire 33 with the wire 28, leading to the lamp. The latch 25, arranged for coöperation with the negative shutter, is provided with an armature 34, connected through the medium of a wire 35, which leads to and is electrically connected with the lamp-terminal 29, as shown.

50 The negative shutter is connected by a wire 36 with the wire 35, and both the latches 25 are held in normal position and returned thereto after operation by coil-springs 37, suitably mounted, as shown.

55 It is to be understood that the circuits just described are duplicated between each respective pair of shutters and the desk of the member to whom said shutters have been assigned, so that said members may individually and accurately control the affirmative and negative shutters, and thereby properly indicate his desire in the matter of voting. As a medium for resetting the shutters each of the shafts 6 is provided with an arm 38, 65 projecting therefrom near one end, the lower

or free end of said arm being longitudinally slotted at 39 to receive pins 40, projecting laterally from a vertically-reciprocating resetting-bar 41. The lower end of the bar projects through the bottom end of the casing, from where it may be suitably operated to reset all the shutters which have been voted, the resetting operation being simultaneous for all shutters voted without effecting those remaining in normal or inoperative 75 position.

In operation, assuming the member desires to vote an affirmative on the questions issued, he depresses the push-button 10, thereby energizing the coil 15, attracting the armature 27 and withdrawing the latch 25 from beneath his affirmative shutter, permitting the same to drop to exposed position in rear of the particular opening 3. By contact of the shutter with the point 30 the lamp-circuit is energized from a suitable source of supply, as a battery 42, through the lamp-wire, through wire 28, wire 33, the shutter, point 30, and wire 29 to the battery. The indicative shutter is operated in exactly the same way, the light-circuit being maintained upon the drop of the shutter to the obvious circuit. It will thus be noted that the shutter-circuit is energized to withdraw the latch and that said latch permanently closes the lamp-circuit, so that said lamp remains burning as long as the voted shutter is in exposed position. On elevating the resetting-rod the resetting-levers 8 are turned upwardly, carrying with them the shutter 100 formally in operative position and causing the free edge of the shutter to ride over and engage the shutter 26 on the respective latch. This operation breaks the lamp-circuit and the lamp is extinguished.

In Fig. 7 I have shown a form of circuit in which the lamp will flash upon a depression of the button and be extinguished as soon as pressure from the button is released. This circuit for both shutters is identical, the lamp-leads 42 43 extending to and being connected to the latches 44, which latches carry armatures 46 to be attracted on the energizing of coils 46 through pressure upon the buttons 10 or 11, connected by a wire 47 to a battery 48 and through a wire 49 to one of the lamp-leads. In this construction the lamp is energized as long as the armature contacts with the core of the coil, being extinguished upon the disconnection thereof. This latter circuit is a simple one and will maintain the lamp continuously energized if the circuit-closing means 10 and 11 are the ordinary switches rather than push-buttons.

Having thus described the invention, what I claim as new is—

1. A votometer comprising a casing, shutters arranged in pairs therein, a circuit including means for supporting each of the shutters in inoperative positions, means for

closing the circuit to actuate said supporting means, and a signal common to and energized in closing either of said circuits.

2. A votometer comprising a casing, shutters arranged in pairs therein, a circuit including means for supporting each of the shutters in inoperative position, means for closing the circuit to actuate the shutter-supporting means, and a signal common to and energized upon the closing of either of said circuits, said signal remaining energized while the signal is in operative position.

3. A votometer comprising a casing, a plurality of shutters arranged in pairs mounted within the casing, a circuit including means for normally holding said shutters in inoperative position, means to close said circuit to energize the shutter-holding means and release the shutter, means for engaging each pair of shutters, and means for simultaneously operating all of said engaging means to reset all shutters in operative position within the casing.

4. A votometer comprising a casing, a plurality of shutters arranged in pairs and mounted within the casing, a normally open circuit for each shutter of each pair, said circuit including means for holding the shutter in inoperative position, independent means for closing each of said circuits to release its shutter, and a single lamp-circuit energized upon the operation of either circuit-closing means.

5. A votometer comprising a casing, a plurality of shutters arranged in pairs and mounted within the casing, a normally open circuit for each shutter of each pair, each of said circuits including means for holding the particular shutter in inoperative position, in-

dependent means for closing each of said circuits to release the particular shutter, and a single normally open lamp-circuit, said lamp-circuit being closed in the movement of either of the shutters to operative position.

6. A votometer comprising a casing, a shutter mounted therein, a normally open circuit including means for holding the shutter in inoperative position, means for closing the circuit to release the shutter, and an independent normally open lamp-circuit, said circuit being closed by the shutter when in operative position.

7. A votometer comprising a casing, a pair of shutters mounted therein, normally open circuits, each including means for holding one of the shutters in inoperative position, and a single means for simultaneously moving each individual pair of shutters from operative position to a position within the influence of the holding means.

8. A votometer comprising a casing, a pair of shutters mounted therein, normally open circuits each including a means for holding one of the shutters in inoperative position, a normally open lamp-circuit, either of said shutters serving to close the lamp-circuit when in inoperative position, and means for moving either of said shutters from operative position into engagement with the holding means, said means thereby breaking the lamp-circuit.

In testimony whereof I affix my signature in presence of two witnesses.

GEORGE E. CAMPBELL.
